FIREARM

Gustav Tauschek, New York, N. Y.

Application November 23, 1933, Serial No. 699,306
In Austria September 15, 1933

19 Claims.

(Cl. 42—4)

My invention relates to firearms, and has for its object to enable a series of successive shots to be fired with the aid of a plurality of projectiles arranged in a novel relation to each other.

5 In the accompanying drawings I have illustrated several forms of ammunition suitable for use with my approved firearms, and also three typical and satisfactory forms of guns or rifles which I have devised for the firing of such ammunition.

Figs. 1 and 3 are longitudinal sections of two forms of such ammunition in the form of cartridges; Figs. 2 and 4 are end views looking from the right of Figs. 1 and 3 respectively and drawn 15 upon an enlarged scale; Fig. 5 is a partial longitudinal section showing a third form of such ammunition, likewise in the form of a cartridge; Fig. 6 is a cross section on line 6—6 of Fig. 5; Fig. 7 is a cross section of still another form of cartridge; Fig. 8 is a perspective view of a sheath which I may employ in conjunction with cartridges such as shown in Figs. 1-7; Fig. 9 is a side view, with parts in longitudinal section, showing still another form of ammunition for use with my improved firearms; Fig. 10 is a partial longitudinal section of a rifle embodying my invention; Figs. 11 and 12 are cross sections on lines 11—11 and 12—12 respectively of Fig. 10; Fig. 13 is a partial longitudinal section of another form of rifle embodying my invention; Fig. 14 is a cross section on line 14—14 of Fig. 13; Fig. 15 is a partial longitudinal section of a third form of rifle embodying my invention; and Fig. 16 is a cross section on line 16—16 of Fig. 15.

35 In Figs. 1 to 7 I have shown four different examples of cartridges suitable for use in my improved firearms, it being understood that I do not wish to restrict myself thereto, but that the cartridge or ammunition may be given other forms 40 or constructions. The several forms of cartridges illustrated are alike insofar as each of them comprises a shell closed at one end and open at the other, with a plurality of bullets or projectiles arranged in tandem fashion within such shell, and 45 with a charge of powder or the like between each two neighboring projectiles. Figs. 1, 3, and 5 show the neighboring projectiles in contact with each other, but this is not an essential feature. The individual projectiles are in close (gas-tight) contact with the inner wall of the shell, so that each charge of powder or the like will be kept quite 50 separate from the adjacent charge or charges.

In Figs. 1 and 2, the cartridge comprises a tube or shell 1 of thin metal closed at one end 55 by a bottom or plug 2 rigidly connected therewith

in any suitable manner, as by slipping the end of the shell over said plug and then exerting pressure by means of rollers or otherwise to establish a firm connection between said two parts. I prefer to provide said cartridge (either the shell or 5 preferably the plug) with a laterally projecting pin 3 which may serve as a convenient handle to grasp the cartridge during the loading of the gun or while removing the empty cartridge shell from the gun after firing. This pin 3 may also co-operate with an ejector of any usual or approved construction, as referred to hereinafter in the description of the rifle illustrated by Figs. 13 and 14. Within the shell 1 are disposed in tandem fashion the bullets or projectiles 4, here shown 10 as spherical balls. These projectiles are fitted into the shell 1 in a gas-tight manner, and when they are made of steel or other relatively hard material, I prefer to make the shell of softer and more compressible material, for instance copper, so as 15 to produce more readily a gas-tight joint between the peripheries of the projectiles 4 and the surrounding cylindrical wall of the cartridge. As illustrated, the innermost projectile 4 engages the bottom or plug 2, and adjacent projectiles are in 20 contact with each other; however, as stated above, such engagement and contact are not essential, although I prefer such arrangement of the projectiles, as it facilitates the proper spacing of the bullets within the cartridge and also offers other 25 advantages, as explained hereinafter. Each of the spaces between adjacent projectiles 4, as well as the space between the plug 2 and the adjacent bullet, contains a charge 5 which in this particular 30 case consists of a mixture of a detonator and a propelling powder, so that such mixture can be 35 set off by a powerful blow delivered locally against the outer surface of the shell 1, preferably at a point about midway between the ends of the space or chamber containing such charge.

The cartridge shown in Figs. 3 and 4 has a shell 1' made of pasteboard or like material and having interior and exterior linings L' and L'' respectively of oiled paper or other suitable material. The metallic bottom plug 2' is provided with the 45 lateral pin or projection 3' and also has at its exposed end an outwardly extending flange 2a against which abuts the adjacent end of the shell 1'. These parts are connected rigidly in any suitable manner, for instance by means of a metal 50 sleeve or ferrule 6 clamping the end of the shell around the bottom plug 2'. The bullets 4, of the same form as in Figs. 1 and 2, are shown in contact with each other, the last or innermost bullet 55 engaging the bottom plug 2'. Each of the spaces

between adjacent bullets, as well as the space between the plug 2' and the innermost bullet, contains a charge 7, which in this case is not a mixture of a propelling powder with a detonator, but 5 is exclusively a propelling charge. Separate detonating charges 8 are located in perforations of the shell 1', said perforations and the charges 8 lying in the same longitudinal plane and being 10 equally spaced, each charge 8 being preferably 15 about midway of the length of the respective propelling charge 7. The detonating charges 8 are held in place by the linings L', L''. The lining L' also has the function of insuring a gas-tight joint at the peripheries of the bullets.

15. With the construction described above, relatively small chambers are left between the contacting bullets 4, owing to the spherical shape of these projectiles. When it is desired to provide greater propelling charges, I may give the 20 projectiles an elongated shape, for instance as shown in Fig. 5. These projectiles have a preferably blunt-nosed body 4' with a rearwardly-extending central spur or stem 4'', the end of which is preferably in contact with the adjacent 25 body 4' or (in the case of the last projectile) with the bottom plug 2'' of the cartridge. The chambers containing the propelling charges 7' may thus be made considerably larger than when employing spherical bullets in contact with each 30 other. I have shown the shell 1'' thickened on one side, the chamber or bore which receives the projectiles and the propelling charges being eccentric to the outer surface of the shell 1'', as shown best in Fig. 6. In this thickened portion 35 I place the detonating charges which may be in the nature of detonating caps 8' of usual type, it being understood that the shell is provided with perforations or recesses to receive these caps. As in Figs. 3 and 4, the detonating charges lie 40 in the same longitudinal plane and are evenly spaced, each detonating charge 8' being in proper co-operative relation to the corresponding propelling charge 7'.

In order to obtain a tight fit at the peripheries 45 of the projectile bodies 4', I might provide the shell 1'' with an inner lining such as described above in connection with Figs. 1 to 4, especially if such shell should be made of pasteboard or like material. Instead of this, I might employ 50 the construction shown in Fig. 5, where the projectile body is illustrated as composed of a core 4^b integral with the spur or stem 4'', and of a jacket or sleeve 4^c surrounding said body and fitted against a shoulder 4^d thereof. The parts 55 4^a, 4^b, 4^d would be made of hard metal, and the jacket 4^c of relatively soft metal, so as to secure a gas-tight joint at the inner surface of the shell 1'', particularly if the latter is made of hard metal.

60. Instead of employing the eccentric arrangement described in connection with Figs. 5 and 6 in order to obtain a one-sided thickening of the cartridge shell, I might, as shown in Fig. 7, make the shell 1^a of uniform thickness throughout the major portion of its circumference, and form it with a thickened longitudinal portion or rib 1^b at the side where the detonating charges or caps 8' are located, the construction in other respects being of the same character as described 65 with reference to Figs. 5 and 6.

In order that cartridges of the types shown 70 in Figs. 1 to 7, especially when their shells are made of pasteboard or of thin metal, may be protected, during storage or handling, against 75 accidental knocks or blows, particularly such as

might cause an explosion of the cartridge, I prefer to encase the individual cartridges, up to the time of their use, in protective sheaths or sleeves, for instance such as shown in Fig. 8. Such a sheath may consist of a piece of sheet 5 metal 9 bent to the form of a cylindrical tube of proper diameter to receive one of the cartridges, the longitudinal edges of such piece being spaced so as to leave a longitudinal slot 9' through which the pin 3 of the cartridge may 10 project. The projecting end of this pin constitutes a handle with the aid of which the cartridge may conveniently be slipped forwardly out of the protective sheath into the cartridge chamber at the end of the gun barrel, in the act of 15 loading the gun.

The ammunition shown in Figs. 1 to 7 consists of cartridges each of which contains a plurality of projectiles in tandem arrangement and a corresponding number of charges. In Fig. 9 I have 20 illustrated another form of ammunition employing a plurality of projectiles in tandem arrangement, with individual charges, but without placing them within the same shell. This ammunition comprises a plurality of projectiles connected with each other at their adjacent ends so as to form a unit which may be loaded into a gun, or rifle in the manner set forth hereinafter with reference to Figs 15 and 16. Each of the projectiles has at its front end a nose 4^e of smaller 30 diameter than the body 4^f of the projectile. This body is of cylindrical tubular character, and its rear end is crimped or otherwise fashioned to fit tightly around the nose 4^e of the next projectile. The nose is preferably ball-shaped, and the connection between adjacent projectiles may be perfectly rigid, so that together they will form a straight rod, or a slight looseness may be provided at the connection, insufficient to impair its gas-tight character, yet giving the flexibility of 40

a ball-and-socket joint so that the series or string of projectiles may be bent or even coiled, which would facilitate storage and shipment and also afford advantages when such string is used in a gun, as explained below. The body 4^f is 45 preferably made with two annular nicks or constrictions 4^g, between which is located the propelling charge 7', preferably with the interposition of a retaining disk 7^h of cardboard or other suitable material generally in contact with the head 50 or nose 4^e of the adjacent projectile. In the forward portion of the body, between the propelling charge 7' and the nose, is disposed a substantially conical holder 10 having an annular channel 10' containing the annular detonating 55 charge 8', so that such charge will be exploded by a blow directed against any point of the outer periphery of the body 4^f, in the transverse plane containing said detonating charge 8'. The holder 10 is also provided with one or more longitudinal channels 10'' extending from the annular channel 10' to and through the nose 4^e, the latter having a central opening 10^a communicating with said longitudinal channel or channels 10''. At its rear end, the holder 10 has a 65 cylindrical portion 10^b in tight engagement with the body 4^f and forming a gas-tight barrier between the detonating charge 8' and the propelling charge 7' located in the same body 4^f. It will be understood that in manufacturing such 70 a series or string of projectiles, a projectile would first be empty, open at the rear end of the body, and uncrimped at such end. The holder 10, with the detonating charge 8' would then be introduced through the open rear end of the body 75

4^e and properly positioned therein, whereupon the forward constriction 4^g would be made to form a backing for the rear end of the body 4^f. Then the propelling charge 7' would be inserted, 5 to be followed by the insertion of the nose 4^e of the next projectile and the connection of the two projectiles, for instance by first crimping the rear end of the front projectile to form the rear constriction 4^g and the elastic ball socket, and 10 then forcing the nose of the rear projectile into such socketed rear end of the front projectile.

In Figs. 10, 11 and 12 I have illustrated a cartridge of the type shown in Figs. 3 and 4, in conjunction with a repeating gun or rifle having 15 a barrel movable relatively to the stock during and immediately after the recoil, and mechanism controlled by such movement of the barrel. The barrel 11 is provided at the breech with a chamber 11^a of proper size to receive one of the cartridges 20 and also with a longitudinal slot 11^b, open at the rear end, adapted to receive the pin 3. At 25 12 I have indicated a breech block, which may be of any suitable construction. At its lower portion, the barrel 11 is provided with a longitudinal series of equidistant openings 11^c, their spacing corresponding to that of the several projectiles (or rather charges) of the cartridge. The barrel 11 together with the breech block 12 and associated parts is movable lengthwise of the 30 stock 13, a spring 14 tending to throw the barrel forward by acting on a projection 11^d of the barrel, the movement of said projection being limited by suitable stop formations on the stock, as will be clear from Fig. 10. The extent of such 35 longitudinal movement is exactly equal to the distance between two adjacent openings 11^c. The stock is formed with a chamber 13' in which a slide 15 is suitably guided for rectilinear movement parallel to the barrel axis. The slide is 40 provided at its front and its rear ends with feet 15' which engage the guideway formed on the lower wall of the chamber 13'; the top of the slide is guided along the bottom of the barrel 11. The top of the slide also constitutes means for 45 making a tight joint with the surface of the barrel at the lower ends of the openings 11^c, which is of particular importance when the cartridge has an outer lining L' of paper or the like and there is danger of gases escaping into 50 the chamber 13'. On the slide 15 is pivotally mounted at 16 a hammer 17 formed with a firing pin 17' in such a position that longitudinal movement of the slide will bring such pin successively into operative relation to the several firing openings 11^c. To the slide 15 is further pivoted, at 55 18, a sear 19 adapted for a locking engagement with the hammer 17 by means of a hook or pawl 19' on the sear fitting against a corresponding shoulder on the hammer. The forward face of 60 the firing pin is as nearly as possible perpendicular to the longitudinal path of the slide 17, while the rear face is inclined, and the same remark will apply to the corresponding faces of the firing openings 11^c. A spring 20 tends to throw the 65 hammer 17 with the firing pin 17' upwardly, and at the same time presses on the sear 19 in such a direction as to tend to throw the upper end of the sear into locking engagement with the hammer 17 and to hold the lower end of the sear 70 against a longitudinal trigger bar 21' extending rearwardly from the trigger 21 which is pivoted to the stock 13 at 22. The trigger is under the influence of a spring 23 which also bears against a pawl 24 pivoted on the stock at 25 and adapted 75 to project into notches 15'' arranged at the lower

portion of the slide 15. There are as many of these notches as the cartridge contains projectiles, and the arrangement of the notches 15'' corresponds to that of the firing openings 11^c, that is to say, the notches form a series or rack 5 extending lengthwise of the rifle, and the distance between adjacent notches is the same as the distance between adjacent firing openings. A spring 26 tends to push the slide 15 forwardly, the pawl 24 normally holding the slide against 10 such movement.

The trigger bar 21' is provided at its rear end with a rearwardly facing hook 21'', located adjacent to, but normally out of operative engagement with, a forwardly facing hook 27' on a rod 15 or bar 27 which extends lengthwise of the rifle. The forward end of the rod 27 extends close to the lower end of the pawl 24, but in the normal position, shown in Fig. 10, the bar permits said pawl to move freely as its upper end slides from 20 one notch of the slide to another in the manner set forth below. The rear end of the rod 27 is pivotally connected at 27'' with a lever 28 fulcrumed on the stock 13 at 29, a spring 30 exerting 25 a forward pressure on the lower portion of said lever. The upper end 28' of the lever 28 extends into an opening of the stock, and is adapted to be projected upwardly through said opening under certain conditions as explained below; normally, however, said opening is covered by the 30 breech block 12 as indicated in Fig. 10, so as to prevent such upward movement or projection of the lever end 28'.

The rifle illustrated by Figs. 10, 11 and 12 has its cartridge chamber 11^a formed to receive cartridges of the type illustrated by Figs. 3 and 4. The pin 3 in this case also has the function of insuring a proper positioning of the cartridge so that its detonating charges 8 will be in registry with the firing openings 11^c when the cartridge 40 is in position. The drawings show the rifle loaded, the hammer cocked and the entire mechanism in readiness for the first shot. Upon pulling back the trigger 21, the trigger bar 21' is raised and thus swings the sear 19 counterclockwise on 45 its fulcrum 18 so that the hook or pawl 19' will release the hammer 17. Under the influence of the spring 20, the hammer swings upwardly on its fulcrum 16, whereby the firing pin 17' is thrown upwardly through the first of the firing 50 openings 11^c and against the first detonating charge 8. This will set off the first propelling charge 7, which is located between the first two projectiles 4, and the foremost projectile will be 55 expelled from the barrel 11. Preferably, as I have stated hereinbefore, the projectiles are in contact with each other, and the rearmost projectile is in contact with the bottom plug 2' so that the second projectile will be held positively against any rearward movement in the cartridge when 60 the first charge is fired. The recoil causes the barrel 11 together with the breech block 12 to move toward the left in Fig. 10. Simultaneously, since the firing pin 17' is in the first firing hole 11^c, and since these parts engage each other along the vertical surfaces which are perpendicular to the movement of the barrel, the hammer 17 is 65 carried along by the barrel during its recoil, together with the slide 15. Since the extent of the recoil is exactly equal to the distance between 70 two adjacent firing openings 11^c and also to the distance between two adjacent notches 15'', the pawl 24, which yields downwardly as the slide 15 moves toward the left, will at the end of the recoil movement drop into the second notch 15''. 75

The spring 26 is, of course, compressed by the movement of the slide 15 during the recoil, but can not return the slide to its original position, since such slide is held by the pawl 24 in engagement with the second notch 15''. Under the influence of the spring 14, the barrel as well as the breech block and the parts connected therewith are then thrown forward into their original position, but the slide 15, being held by the pawl 24, remains in its new position, one step farther to the left than originally, and the firing pin 17' is therefore now in position to explode the second charge of the cartridge. During the forward movement of the barrel under the influence of the spring 14, the inclined rear face of the firing opening 11c in which the firing pin is at that time, acts on the correspondingly inclined rear face of the firing pin and depresses the latter so as to clear the path of the barrel and at the same time put the spring 20 under tension. If the person has released the trigger 21 immediately after pulling it, the hammer 17, at the end of its downward movement, will be caught by the sear 19, these parts therefore again assuming the relative position shown in Fig. 10. It will, of course, be understood that the lower portion of the hammer 17 and the upper portion of the sear, at the hook or pawl 19', are so fashioned that the sear will yield as the lower end of the hammer passes from above the hook 19' to below the same. Under the conditions just described, a single shot will be fired and the parts will then be in the same position as shown in Fig. 10 except that the slide 15 and the hammer 17 will be one step to the left. If instead of releasing the trigger immediately after pulling it, the person keeps the trigger depressed, then, as the barrel is thrown forward by the spring 14 after the firing of the first shot, the sear 19 will not be in position to catch and hold the hammer 17, and as a result thereof, the hammer, after having been thrown downwardly so as to compress the spring 20, will at once again be thrown upwardly by the spring, to bring the firing pin 17' against the second detonating charge 8, thereby exploding the second propelling charge and causing the second bullet to be fired from the rifle. Thus, as long as the trigger 21 is kept retracted, the rifle will act as a repeating rifle, firing one shot after another, the slide 15 travelling one step to the left between each two successive shots so as to bring the hammer 17 successively into the several firing positions. After the last recoil, the hammer will be in the position illustrated in dotted lines 55 and the firing pin will be in registry with a solid surface of the barrel, that is to say, beyond the last firing opening 11c to the left. The slide 15 will be in the position in which its last notch 15'' at the right will be engaged by the pawl 24. Thus, the spring 26 will be fully compressed and ready to restore the slide 15 to the initial position whenever released from the holding action of said pawl. The hammer will be caught by the sear 19 as soon as the person releases the trigger 21. The breech of the rifle is then opened by manipulating the breech block 12 in any well known or approved manner, whereby such breech block will be carried rearwardly (to the left in Fig. 10) until its forward end uncovers the opening of the stock into which the upper end 28' of the lever 28 extends. As soon as the breech block 12 no longer engages said lever end 28', the spring 30 will throw the lever 28 counterclockwise, whereby the forward end of the rod 27 will be caused to engage the lower arm of the

pawl 24 and swing the latter counterclockwise out of engagement with the slide 15. The latter will then be thrown toward the right by the spring 26 and will thus be brought back to the original position shown in Fig. 10. It will be understood that while the breech of the rifle is open, the spent cartridge is extracted from the barrel and a new cartridge inserted. Then the breech block is again brought to its normal position which causes the lever 28 to swing clockwise and the rod 27 to move away from the pawl 24 so that the latter, under the influence of the spring 23, is thrown upwardly into engagement with the first notch of the slide 15, as in Fig. 10.

Since the insertion of a new cartridge into the cartridge chamber of the barrel takes place while the breech of the rifle is open, there is some danger of premature firing, for instance if the trigger should be pulled after the cartridge has been inserted, but before the breech has been closed. To guard against this possibility, I have provided the hooks 21'' and 21'. Normally, that is to say, when the breech block is in the closed position, these hooks are separated from each other and have no function. When, however, the breech block is moved rearwardly and the lever 28 swings counterclockwise under the influence of the spring 30, the forward movement of the rod 27 brings the hook 21' into locking engagement with the hook 21'' so as to prevent any accidental movement of the trigger and to provide a safety lock therefor during all the time that the breech of the rifle is open. As soon as the breech block again reaches its closing position, the hook 21' moves rearwardly to disengage the hook 21'' and thus leave the trigger free for normal operation.

While Figs. 10, 11 and 12 show the rifle chambered to receive cartridges of the specific type shown in Figs. 3 and 4, it will be understood that only a very slight change is required in the chambering of the rifle barrel to adapt it for the reception of cartridges such as shown in Figs. 1 and 2 or of cartridges of the type shown in Figs. 5, 6 and 7. It will be understood that in each case the spacing of the firing openings in the barrel would correspond to the spacing of the notches on the slide 15 and also to the spacing of the charges in the cartridge. In the case of cartridges such as shown in Figs. 1 and 2, the pin 3 would not be required to give the cartridge any definite circumferential position in the barrel, because the cartridge charge would be exploded by a blow against any point of its periphery between two projectiles, since in this particular case the detonating agent is distributed uniformly within the entire charge, instead of being located at a definite point of the periphery as in the cartridges shown in Figs. 3 to 7.

In Figs. 13 and 14 I have shown a rifle having the barrel 11' the cartridge chamber 11c of which is fashioned to receive a cartridge having a shell of the type shown in Figs. 5 and 6, while the arrangement of projectiles and charges is of the character shown in Figs. 3 and 4. It will be noted that the cartridge chamber 11c of the barrel is eccentric so that the bore of the cartridge will be in axial alignment with the bore of the barrel. In this form the barrel is stationary relatively to the stock 13, that is to say, this form of my invention does not contain any recoil operated mechanism. In addition to the firing openings 11d of the same character as in Fig. 10, the barrel is provided with a recess 11e located in advance of the foremost firing opening 75

11^a, at a distance therefrom corresponding to the spacing of the firing openings. The breech block 12' may be of any customary or approved construction and I have also indicated at E an 5 ejector of any approved type which is adapted to co-operate with the flange at the rear end of the cartridge. The hammer 17" is fulcrumed at 16' on the slide 15 which has feet 15' and notches 15" substantially as in the construction 10 shown in Fig. 10. The hammer carries a firing pin 17^a which a spring 20 tends to project into the firing position. Furthermore, the hammer has a lateral projection 17^b adapted to co-operate with the teeth of a stationary rack 31. The forward 15 faces of these teeth are inclined, while their rear faces are approximately vertical, or more accurately speaking, slightly curved to correspond to the path of the projection 17^b. The hammer is also provided with a handle 17^c projecting outwardly. The notches 15" of the slide are adapted to receive the pawl-like end 24' of the trigger 21" provided with a longitudinal slot 21^a through which extends the stationary fulcrum pin 22. The spring 23' tends to pull the trigger into the 20 position illustrated, in which the pin 22 is at the rear end of the slot 21^a and in which the pawl-like end 24' is clear of the notches 15".

The operation of this form of my rifle is as follows: Fig. 13 shows the initial position of the 25 parts, before the trigger is pulled for the first shot. Upon retracting the trigger 21", it first swings on the pin 22 so as to raise the end 24' into the first notch at the extreme left of the slide 15. The trigger and the slide thus become 30 locked for movement in unison. Further retraction of the trigger will therefore not only pull the trigger backward causing it to slide along the pin 22 to the extent permitted by the slot 21^a, which is horizontal during this sliding movement, 35 but the slide 15 will share in this rearward movement of the trigger. The length of the slot 21^a is so proportioned as to give the slide 15 a longitudinal motion corresponding exactly to the spacing of the firing openings 11^a and of the notches 15". As the slide 15 moves to the rear, 40 the inclined forward face of the first tooth of the stationary rack 31 will by its co-operation with the lateral projection 17^b of the hammer 17", cause such hammer to swing on its fulcrum 45 16' to remove the firing pin 17^a downwardly from the recess 11^c and at the same time put the spring 20 under tension. As soon as the projection 17^b clears the free end of said first rack tooth, the spring 20 will throw the hammer and 50 the firing pin upwardly, said pin at that time having reached a position in registry with the first firing hole 11^d. The first charge will thus be exploded to fire the first projectile of the cartridge. In this form of my invention, a separate 55 pull on the trigger is required for the firing of each shot. Upon the release of the trigger, the slide 15 and the hammer 17" will remain in their new position, that is to say, with the firing pin in operative relation to the first firing hole, 60 the lateral projection 17^b, by its co-operation with the rack 31, holding the parts in this position. The trigger 21" upon being released will be pulled forwardly by its spring 23' so that the pawl-like end 24' of the trigger will come into 65 registry with the second notch 15' from the left. Upon then again pulling the trigger rearwardly it will cause the slide 15 to be moved another step to the left, thereby bringing about the firing of the second projectile. By a repetition of these 70 operations, the projectiles will be fired in succes- 75

sion. After the firing of the last projectile the slide 15 and the parts connected therewith will be brought back manually to the position illustrated, the handle 17^c being used to swing the hammer 17" downward until the projection 17^b 5 is clear of the rack 31. In this construction, the barrel has no longitudinal slot such as the slot 11^b of Figs. 10 and 12, since cartridges of the type shown in Figs. 5, 6 and 7 are provided, at the lower portion of the flange 2^a, with a flat 10 which in conjunction with a corresponding surface of the cartridge chamber serves to position the cartridge properly, the lateral pin 3 or 3' being omitted.

In Figs. 15 and 16 I have illustrated a rifle 15 adapted to fire ammunition of the character shown in Fig. 9. The barrel 11" is mounted to slide lengthwise relatively to the stock 13" and carries at its rear end a holding pawl 32 fulcrumed on the barrel at 32' and pressed inwardly by a spring 33. Instead of a single holding pawl 32, I may employ a plurality of them, for instance three at 90° from each other, as indicated in Fig. 15. In the position illustrated another pawl 34 is arranged opposite to the upper 25 pawl 32. This pawl 34 is pivoted at 34' upon an arm 35 fulcrummed on the stock 13" at 35'. A spring 36 tends to throw the pawl 34 toward the upper pawl 32. With the barrel is connected a longitudinal rod 11^c suitably guided in the stock 30 13" and surrounded by the spring 44' the function of which is to restore the barrel to its forward position after the recoil. With the arm 35 is pivotally connected at 35" a link 37 fulcrummed at 37' on a bracket integral with the barrel 11". The firing pin 17^a is located in a proper position 35 to register with the detonating charge 8' when the rear end of a projectile is in engagement with the front ends of the pawls 32 and 34 as illustrated in Fig. 15. This firing pin is preferably 40 spring pressed as indicated so that it will have a tendency to move away from the bore of the barrel. The hammer 17^c is fulcrumed at 16" on the stock 13" and is under the influence of a spring 20 tending to throw it against 45 the firing pin 17^a. The hammer is also provided with a lateral projection 17^b which in the position illustrated co-operates with the front 50 end of the trigger bar 21^c to hold the hammer in the position in which the spring 20 is under 55 full tension. The trigger 21^b is pivoted at 22, and a spring 38 tends to throw it into the position illustrated, where the trigger arm 21^c engages a stop pin 39. The lateral projection 17^b is also adapted to co-operate with the pawl 40 fulcrummed 60 on the barrel at 40' and pulled into the lower position illustrated, by means of a spring 41. As it may be desirable to prevent accidental firing of the rifle, I have indicated at 42 a safety catch 65 of the eccentric type which can be turned manually either to a position where the trigger bar 21^c is held locked against the stop pin 39, or into a position where the trigger and trigger bar are 70 free for the operation of the rifle.

Fig. 15 shows the string of projectiles in proper 65 position for the firing of the first shot. It will be noted that in this position the pawls 32 and 34 engage the rear end of the second projectile, and the firing pin 17^a is in registry with the detonating charge 8' contained in the second projectile. 70 This detonating charge, however, is not intended to fire the second projectile, but the first. Upon pulling the trigger 21^b, the trigger bar 21^c will be depressed so as to clear the hammer projection 17^b and release the hammer, which under 75

the influence of the spring 20 will be thrown against the firing pin 17^d exploding the detonating charge 8' contained in the second projectile. Through the channel or channels 10" and the opening 10^a the hot gases produced by the detonation of this charge will reach the propelling charge 7' of the projectile ahead, that is the first projectile in this case. This charge will be set off and the first projectile will be fired from the rifle, the rear end of such projectile being sufficiently elastic to pull it clear of the nose of the second projectile, the latter remaining stationary as any rearward movement of the second projectile relatively to the barrel is prevented by the pawls 32 and 34. The second projectile fits tightly into the opening at the rear end of the barrel, and constitutes a breech closure which the pawl or pawls 32 prevent from moving rearwardly in relation to the barrel. The barrel 20 then recoils, carrying with it the string of projectiles as well as the pawl 32 which remains in engagement with the rear end of the second projectile. At the same time the link 37 is carried back by the recoiling barrel, and swings the arm 35 on its fulcrum 35'. As the pivot 34' of the pawl 34 is at a considerably greater distance from the fulcrum 35' than the pivotal connection 35" of the link 37, the pawl 34 is carried back considerably farther than the extent of the recoil, 30 and slides rearwardly over and beyond the third projectile as the latter moves with the recoiling barrel. At the end of the recoil the pawl 34 has been carried to the left of the rear end of the third projectile. When then the barrel moves 35 forward under the influence of the spring 14', the pawl 34, being in engagement with the rear end of the third projectile, moves such projectile forwardly, together with all the projectiles connected therewith, the pawl 32 yielding to permit 40 such movement and dropping into position behind the rear end of the third projectile as soon as the forward movement of the barrel has been completed, when the parts will have resumed the position shown in Fig. 15, except that the pawls 45 32, 34 will now engage the rear end of the third projectile, the string of projectiles having been advanced relatively to the barrel by the distance of one projectile. This successive feed of the projectiles occurs after each shot. During the 50 recoil of the barrel the pawl 40 is carried along until its forward end passes from a position in front of the hammer projection 17^c, to a position in the rear thereof, the inclined face at the end of the pawl 40, and the spring 41 permitting 55 the pawl to yield as it passes over the projection 17^c. When the barrel is thrown forward by the spring 14', the forward end of the pawl 40, which is preferably substantially perpendicular to the movement of the barrel, engages the rear 60 face of the projection 17^c and thus swings the hammer 17^e back slightly beyond the position shown in Fig. 15, the trigger bar 21^c rising to the position illustrated so as to lock the hammer, if the trigger has been released. If, however, the 65 trigger has not been released, but is kept retracted, the hammer will not be locked by the trigger bar, but upon the pawl 40 at the end of its forward movement clearing the upper edge of the projection 17^c, the hammer will at once be 70 thrown against the firing pin 17^d, and as long as the trigger is held depressed, one projectile will be fired after another in rapid succession until the last projectile but one has been fired. At the end of this operation, there will be no further feed of the string of projectiles, because the

pawl 34 when moved backward will find no projectile to advance. The last projectile will thus be left in a position corresponding to that of the second projectile shown in Fig. 15. When the next string or chain of projectiles is introduced into the rifle, the nose of the first projectile of the new string will be forced into the elastic socket at the rear end of the last projectile of the preceding string, and thus said last projectile will be connected with the new chain 10 or string of projectiles. The gunner will by hand feed the new chain of projectiles forwardly until the projectile left over from the previous string of projectiles is in the position of the front projectile shown in Fig. 15. Instead of this, firing 15 may be stopped (by releasing the trigger 21) before the last projectile has entered the rifle, so that the first projectile of the new chain will be connected with the last projectile of the preceding chain while said last projectile is exposed 20 and readily accessible for manipulation. Firing may then be resumed in the same manner as described above. A washer 43 made of asbestos or other suitable material is preferably employed at the rear end of the barrel to obtain a gas-tight 25 joint. While in Figs. 10 to 14 I have shown rifles adapted to use a single cartridge having a number of projectiles in tandem arrangement, it will be understood that I might use, in connection with my invention, clips holding a plurality of 30 additional cartridges of the type herein set forth to be fed to the firing position successively by mechanism of a type well known in the art in connection with repeating or magazine rifles.

While I have illustrated mechanical firing 35 mechanisms, I desire it to be understood that other kinds of firing mechanisms may be employed, particularly electrical firing mechanisms of any well known or approved type.

While I have described and illustrated my invention as applied to rifles, it will be obvious that it may be used in connection with other firearms, for instance other small arms such as pistols and carbines, or larger arms such as machine guns, or even cannon or other ordnance.

When employing cartridges containing a plurality of projectiles and separate charges, as in Figs. 1 to 7, 10, and 13, I prefer to graduate the amount of power of the charges, the charge for the front projectile being the largest or strongest, and the other charges decreasing progressively to the last charge (the one at the rear end of the cartridge). The purpose is to insure correct and uniform trajectories for all the projectiles notwithstanding the fact that the front projectiles have to travel a shorter distance before leaving the rifle than the rear projectiles.

I claim:

1. A firearm comprising a stock, a recoil barrel movable lengthwise of said stock, means holding a plurality of projectiles in tandem on the longitudinal axis of the barrel, firing mechanism, and means, operated by the longitudinal movement of the barrel relatively to the stock, for establishing successively an operative relation between said firing mechanism and the several projectiles.

2. A firearm comprising a stock, a recoil barrel movable lengthwise of said stock and having a plurality of firing points at different distances from the end of the barrel, said barrel being adapted to receive a cartridge containing a plurality of projectiles and charges spaced to register with said firing points, firing mechanism

movable lengthwise of the stock into operative relation with the several firing points of the barrel, and means, operated by the longitudinal movement of the barrel relatively to the stock, for bringing said firing mechanism into operative relation with successive firing points of the barrel as successive shots are fired.

5. A firearm comprising a stock, a recoil barrel movable lengthwise of said stock and having a plurality of firing points at different distances from the end of the barrel, said barrel being adapted to receive a cartridge containing a plurality of projectiles and charges spaced to register with said firing points, a slide movable lengthwise of the stock, firing mechanism carried by said slide and normally movable therewith in one direction into operative relation with the several firing points of the barrel, means for normally preventing movement of said slide in the opposite direction, and means for causing the longitudinal movement of the barrel relatively to the stock to carry said slide with the firing mechanism into operative relation with successive firing points of the barrel as successive shots are fired.

4. A firearm comprising a stock, a recoil barrel movable lengthwise of said stock and having a plurality of firing points at different distances from the end of the barrel, said barrel being adapted to receive a cartridge containing a plurality of projectiles and charges spaced to register with said firing points, a slide movable lengthwise of the stock, a spring urging said slide to travel in one direction, holding means for normally preventing movement of said slide in the said direction, firing mechanism carried by said slide and including a firing pin which in the firing position and during the recoil of the barrel engages the barrel at one of its firing points to couple the barrel and the slide for movement in unison during the recoil and put said spring under tension, means whereby during the forward movement of the barrel following the recoil the firing mechanism and the slide will be uncoupled from the barrel so that such forward movement will bring the next firing point of the barrel into operative relation with the firing mechanism, and means for releasing the slide from said holding means to permit the spring to restore the slide to its original position.

5. A firearm comprising a stock, a recoil barrel movable lengthwise of said stock and having a plurality of firing points at different distances from the end of the barrel, said barrel being adapted to receive a cartridge containing a plurality of projectiles and charges spaced to register with said firing points, a slide movable lengthwise of the stock, a spring urging said slide to travel in one direction, holding means for normally preventing movement of said slide in the said direction, firing mechanism carried by said slide, means for causing the recoil of the barrel to carry the firing mechanism and the slide into operative relation with successive firing points of the barrel as successive shots are fired, and simultaneously to put said spring under tension, and means for releasing the slide from said holding means to permit the spring to restore the slide to its original position.

70. 6. A firearm comprising a stock, a recoil barrel movable lengthwise of said stock and having a plurality of firing points at different distances from the end of the barrel, said barrel being adapted to receive a cartridge containing a plu-

rality of projectiles and charges spaced to register with said firing points, a breech block movable to open or close the breech of said barrel, a slide movable lengthwise of the stock, a spring urging said slide to travel in one direction, holding means for normally preventing movement of said slide in the said direction, firing mechanism carried by said slide, means for causing the recoil of the barrel to carry the firing mechanism and the slide into operative relation with successive firing points of the barrel as successive shots are fired, and simultaneously to put said spring under tension, and means, controlled by the movement of the breech block to the breech-opening position, for releasing the slide from said holding means to permit the spring to restore the slide to its original position.

7. A firearm comprising a stock, a recoil barrel movable lengthwise of said stock and having a plurality of firing points at different distances from the end of the barrel, said barrel being adapted to receive a cartridge containing a plurality of projectiles and charges spaced to register with said firing points, a breech block movable to open or close the breech of said barrel, firing mechanism movable lengthwise of the stock into operative relation with the several firing points of the barrel, means, operated by the longitudinal movement of the barrel relatively to the stock, for bringing said firing mechanism into operative relation with successive firing points of the barrel as successive shots are fired, a trigger controlling said firing mechanism, and safety means, controlled by the movement of the breech block to the breech-opening position, for locking said trigger against accidental operation.

8. A firearm comprising a barrel having a plurality of firing points at different distances from its end, firing mechanism including a hammer adapted by its striking action to explode detonating charges at the several firing points individually, said hammer being movable lengthwise of the barrel into operative relation with the several firing points thereof, and a trigger movable bodily lengthwise of the barrel and having means to carry the hammer along with the trigger in such bodily lengthwise movement into operative relation with a different firing point of the barrel at each successive operation of the trigger.

9. A firearm comprising a stock, a barrel carried by said stock and having a plurality of firing points at different distances from the end of the barrel, a slide movable lengthwise of the stock and barrel, mechanism including a hammer adapted by its striking action to explode detonating charges at the several firing points individually, said hammer being mounted on said slide and adapted to be carried by the movement thereof into operative relation with the several firing points of the barrel, means for causing said hammer to operate during the movement of the slide, and a trigger movable bodily lengthwise of the stock and barrel and having means to engage said slide and shift the same in unison with such bodily lengthwise movement of the trigger to carry the hammer into operative relation with a different firing point of the barrel at each successive operation of the trigger.

10. A firearm comprising a stock, a recoil barrel movable lengthwise of the stock, means holding a plurality of connected projectiles in tandem on the longitudinal axis of the barrel, firing mechanism, and means, operated by the longitudinal movement of the barrel, for feeding the

- connected projectiles forwardly in the barrel to bring successive projectiles into operative relation to the firing mechanism as successive shots are fired.
- 5 11. A firearm comprising a stock, a recoil barrel movable lengthwise of the stock and adapted to receive a plurality of projectiles and charges connected in tandem fashion, firing mechanism, holding mechanism mounted on the barrel and 10 constructed to prevent rearward movement of the projectiles relatively to the barrel while permitting forward movement of the projectiles, and feed mechanism movably mounted on the stock and operatively connected with the barrel, and 15 engaging the connected projectiles, the operative connection of the feed mechanism with the barrel being so constructed that during the recoil of the barrel said feed mechanism will sweep rearwardly along the connected projectiles, at least 20 the distance of one projectile length, to engage another projectile, while during the succeeding return of the barrel to its normal position the feed mechanism will feed the connected projectiles one projectile length forward relatively to 25 the barrel.
12. A firearm comprising a barrel having a breech open rearwardly, means holding a plurality of connected projectiles and charges in tandem on the longitudinal axis of the barrel, 30 means for holding one of said projectiles in a position in which it closes the breech of the barrel, and means for feeding the connected projectiles forwardly in the barrel to bring successive projectiles into firing position as successive shots 35 are fired.
13. A firearm comprising a barrel adapted to receive a plurality of projectiles and charges connected in tandem fashion, means for holding one of said projectiles in a position in which it closes 40 the breech of the barrel, and means, operated automatically every time a shot is fired, for feeding the connected projectiles forwardly in the barrel to bring successive projectiles into firing position as successive shots are fired.
- 45 14. A firearm comprising a barrel having a breech open rearwardly, means holding a plurality of projectiles in tandem on the longitudinal axis of the barrel, means for holding one of said projectiles in a position in which it closes the 50 breech of the barrel, and means for feeding the said projectiles in unison forwardly in the barrel to bring successive projectiles into firing position.
15. A firearm comprising a barrel having a breech open rearwardly, means holding a plurality of projectiles in tandem on the longitudinal axis of the barrel, means for holding one of said projectiles in a position in which it closes the 5 breech of the barrel, and means, operated automatically every time a shot is fired, for feeding the said projectiles in unison forwardly in the barrel to bring successive projectiles into firing position.
16. A firearm comprising a barrel having a breech open rearwardly, means holding a plurality of projectiles in tandem on the longitudinal axis of the barrel, means for holding one of said projectiles in a position in which it closes the 15 breech of the barrel, and means for feeding the said projectiles in unison axially through the open breech of the barrel to bring successive projectiles into firing position.
17. A firearm comprising a barrel having a 20 plurality of firing points at different distances from the end of the barrel, said barrel being adapted to receive a cartridge containing a plurality of projectiles and charges spaced to register with said firing points, firing mechanism 25 movable lengthwise into operative relation with the several firing points of the barrel, and means, operated by the discharge of the firearm, for bringing said firing mechanism into operative relation with successive firing points of the bar- 30 rel as successive shots are fired.
18. A firearm comprising a barrel, means holding a plurality of projectiles in tandem on the longitudinal axis of the barrel, firing mechanism including a single firing pin, means for effecting 35 relative lengthwise movement to establish successively an operative relation between the said firing pin and the several projectiles, and means for causing the several projectiles to be fired successively by the same firing pin as the latter 40 is in operative relation with the respective individual projectiles.
19. A firearm comprising a barrel, means holding a plurality of projectiles in tandem on the longitudinal axis of the barrel, firing mechanism 45 including a single firing pin, and means for effecting relative lengthwise movement to establish successively an operative relation between the said firing pin and the several projectiles.

GUSTAV TAUSCHEK.
